ULTRA-SHORT WAVE RECEIVING APPARATUS

Walter Kriebel, Berlin, Germany, assignor to
 Telefunken Gesellschaft für Drahtlose Tele-
 graphie m. b. H., Berlin, Germany, a corpo-
 ration of Germany

Application October 28, 1937, Serial No. 171,443
 In Germany September 2, 1936

3 Claims. (Cl. 250—27.1)

The present invention relates to a tube de-
 tector for receiving ultra-short waves. This de-
 tector is more sensitive than a bolometer and
 exhibits above all a uniform response.

5 The inventive idea is as follows:—

The emission source or cathode of a discharge
 tube, e. g. of a diode, is directly supplied with
 the high-frequency receiving current so that
 heating or additional heating is effected thereby.
 10 As the emission of a cathode, so long as the ap-
 plied plate voltage by far exceeds the saturation
 voltage, greatly depends on the heating, relatively
 small variations of the receiving currents may be
 made perceptible in this manner. E. g. a heat-
 15 ing current variation by 1% yields an emission
 variation of about 20%. One reason why the
 plate voltage must exceed saturation voltage is
 to prevent space charge between the cathode and
 the plate.

20 A relatively simple arrangement results, if a
 diode is used as receiving tube and one dipole
 half each is attached to the ends of the straight
 cathode.

As the filament energy consumption varies for
 25 a given resistance of the spot to be heated with
 the square of the current the cathode, prefer-
 ably, is initially heated by a constant but ad-
 justable, as may be required, direct current and
 the received high-frequency oscillations are used
 30 only to render an additional heating. To avoid
 the high-frequency leaking off through the heat-
 ing current leads, one may either design the
 emissive spot to be very small so that it prac-
 tically lies only in the voltage node of the dipole,
 35 or tune the heating current leads by means of a
 metal slider which is insulated from the heating
 current leads and is sliding on them. Further,
 one may shape the emissive spot to an indirectly
 heated cathode. In this case the heater is shaped
 40 to run bifilarly within the emission layer support
 and the lead-in wires are placed exactly at the
 voltage node. With extraordinary short waves it
 may occur, that the small dipole halves intended
 to collect the radiation lie at the greater part
 45 within the vacuum vessel or in the wall of the
 tube. In such case it is recommendable to make
 the radiation collector equal to an odd number
 of half wave lengths, e. g. $3/2\lambda$, and to arrange
 that one voltage node each lies in the centre
 50 of the emissive spot and at the seals through
 the wall of the vessel respectively; or, alternately,
 one mounts the tuned dipoles, i. e. dipole de-
 signed to have a certain length, together with the
 emission source within the vacuum vessel.

55 In the Figs. 1 to 3 of the accompanying draw-

ing embodiments of the invention are shown.
 Therein is designated by:

1 the plate of a directly heated diode 9; 2 and
 5 3 a dipole joined to the terminals of the fila-
 ment 4 (2 and 3 are tuned to $\lambda/2$ of the decimeter
 wave to be received); 5 a variable resistance for
 adjusting the heating current supplied by the
 heating battery 6 and thereby at the same time
 10 the emission of the filament 4 to the most fa-
 vorable value, 7 an indicator, e. g. a head phone,
 15 8 the plate battery. The filament consists of a
 tungsten-, thoriated or oxide-coated wire. The
 oxide-coated filament, e. g., is made of a core of
 platinum or a platinum-iridium alloy to which
 20 oxides of the alkaline earth metals, as calcium-
 strontium- or barium-oxide, together with var-
 25 ious admixtures are pasted, fused or sintered on.

The performance of the device is as follows:—

The modulated high-frequency, which oscil-
 lates on the dipole together with the inserted
 25 filament, varies the heating and thereby the emis-
 sion of the filament in time with the modulating
 amplitude. The emission variations produce
 30 plate current variations in the plate circuit,
 which are listened to by means of head phones
 either directly or through an amplifier.

To reduce still more the thermal inertia of
 the filament, the filament 4 may be given the
 35 shape of a platinum tube about 2μ in thickness,
 which is covered with oxides, if required.

Fig. 2 shows practically the same receiving de-
 vice as Fig. 1. Like reference numerals represent
 like circuit elements. Only the cathode 10 has
 been varied. The preferably thin-walled emis-
 sive sleeve is initially heated by a heater being
 40 situated within the sleeve. The wires of
 the heater are running in opposite directions
 and led out at the centre of the emissive sleeve.
 In Fig. 3 an arrangement is shown in its prin-
 ciple, adapted in particular to receive very short
 45 waves. To avoid losses at the seals of the dipole
 through the wall of the vessel and to be able to
 make the radiation collecting part without the
 vessel of sufficient length, the whole arrange-
 ment comprising the radiation collector and the
 50 cathode, has been made equal to an odd number
 of half wave lengths, e. g. $3/2\lambda$, $5/2\lambda$ etc. The
 cathode 11 and the seals 12 and 13 are positioned
 each at one voltage node of the stationary waves
 built up on the total arrangement.

In the operation of the device of the invention,
 it will be appreciated that the extra filament
 heating provided by the waves collected by the
 antenna gives plate current in proportion to the
 amplitude of the extra heating current, and hence

in proportion to the amplitude of the received waves. This extra plate current, varying in accordance with the wave amplitude, constitutes a modulation frequency current through the headphones.

5 What is claimed is:—

1. A tube detector comprising a space discharge device, radiation collectors attached to the terminals of the cathode of said discharge device, 10 an indicator coupled to the plate circuit of said discharge device, the said radiation collectors together with said cathode being so arranged that the total length amounts to $3/2\lambda$ and one voltage node each occurs at the seals through the wall 15 of the device and at the centre of said cathode where λ is the length of the collected wave.

2. A tube detector comprising a space discharge device, radiation collectors attached to the ter-

minals of the cathode of said discharge device, an indicator coupled to the plate circuit of said discharge device, the said radiation collectors together with said cathode being so arranged that the total length is an odd multiple including unity 5 of half the length of the collected wave.

3. A tube detector comprising a space discharge device, radiation collectors attached to the terminals of the cathode of said discharge device, an indicator coupled to the plate circuit of said 10 discharge device, the said radiation collectors together with said cathode being so arranged that the total length is an odd multiple including unity of half the length of the collected wave, and a voltage node occurs at the center of said 15 cathode.

WALTER KRIEBEL.
